UNITED STATES PATENT OFFICE.

THOMAS H. SEELY, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,278,232.

Specification of Letters Patent. Patented Sept. 10, 1918.

Application filed November 8, 1915. Serial No. 60,309.

To all whom it may concern:

Be it known that I, THOMAS H. SEELY, a citizen of the United States, residing at Malden, in the county of Middlesex and 5 State of Massachusetts, have invented certain Improvements in Lasting-Machines, of which the following description, in connection with the accompanying drawings, is a specification, like reference characters on the 10 drawings indicating like parts in the several figures.

This invention relates to lasting machines, and more particularly to that type of lasting machine which is adapted to work on 15 different portions of the upper materials successively as described in United States Letters Patent, No. 584,744, dated June 15, 1897.

In machines of this type, devices, such as 20 pincers, are actuated to grip and pull or updraw the upper materials and overdraw or lay them over upon the innersole, and a wiper is given movement to engage the upper materials and press or wipe them 25 smoothly upon the innersole. The upper materials are secured in lasted position by tacks, which are fed singly into an aperture in the wiper prior to each advance movement thereof and driven by tack-driving 30 means at the conclusion of the wiper advance. Machines of this type are also provided with means for imparting lateral and axial turning pincer movements to plait the upper materials at those portions of the shoe 35 where excessive fullness of stock occurs, said means being under the operator's control, which enables him to plait the upper materials to the degree desired where necessary or suspend the plaiting movements.

40 While lasting certain portions of the shoe, as for instance, about the heel seat, the action of the wiper alone is sufficient to overlay the upper materials, and at such time the gripping and overdraw movements 45 of the pincers may conveniently be dispensed with as may also their plaiting movement, thus relieving the machine of this work, decreasing the machine vibration, and the wear that would otherwise ensue. 50 At other times, it may be desirable to con-

tinue the gripping and overdraw movement of the pincers without the plaiting movement where the fullness of stock is not excessive, in which case the pincers will be given a straight updraw and overdraw action. 55

During the lasting operation on this type of lasting machine, and the driving of the fastenings or tacks, the shoe is ordinarily held by both hands of the operator, while 60 his foot maintains the starting and stopping treadle depressed to continue the machine in operation. It is inexpedient for him to release the shoe or to disturb the position of his foot while the operation of 65 lasting continues, and yet it is desirable that he have personal control of the pincer gripping and overdraw movements, and be able at will to suspend or introduce such movements, as well as to suspend or introduce at will the pincer plaiting movements. 70

It is an important object of the present invention, therefore, to improve lasting machines of this type by securing therein the results indicated, and to this end an important feature of the invention comprises the provision in a lasting or like machine adapted to work on different parts of the upper materials successively, of means for suspending or introducing at will the pincer 80 gripping and overdraw movements independently of other parts of the machine and while such parts continue in previously established operative relation. By the provision of such means, the operator may, 85 while holding the treadle depressed to continue the machine in uniform operation, and while still holding the work with both hands; either suspend or introduce the pincer movements and render them operative or inoperative in placing the upper materials in lasted position without at the same time changing the relations of other parts of the machine. 90

Another broad feature of the invention 95 consists in the provision of improved means movable at will to a position to control some of the pincer movements and to another position to control other of said pincer movements. 100

On starting the lasting operation in this type of lasting machine, it is desirable that the pincers should grip and overdraw the upper as the machine makes its first revolution, and thereafter that such gripping and overdrawing action of the pincers be continued or discontinued at the will of the operator according to the condition of the work. Another feature of the invention, therefore, consists in means for insuring that the pincer gripping and overdraw movements will be effective on starting the machine in combination with means for rendering ineffective or continuing at will the pincer movements following the first cycle of the machine operation.

The above several features of the invention and others not hereinbefore specified as well as certain novel constructions and combinations of parts, will now be described in connection with a machine of the type referred to in the aforesaid Letters Patent, but it is to be understood that the invention is not to be considered as necessarily restricted in its application to this type of machine, nor to the particular details shown and described by way of explanation of the invention.

Referring to the accompanying drawings in which the same reference characters denote similar parts throughout the several views:—

Figure 1 is a side elevation of a lasting machine with the present improvements applied thereto;

Fig. 2 is a perspective view of parts detached and showing the relation of the pincer controlling elements;

Fig. 3 is an enlarged detached detail of the clutch members for controlling the operative or inoperative condition of the pincer-controlling cam;

Fig. 4 is a detail partly in section, of the means for operating one of the clutch-carrying members as the machine is started and stopped;

Fig. 5 is a side elevation on an enlarged scale, showing certain of the parts illustrated in Fig. 1, pertaining more particularly to the pincer control mechanism and tack saver;

Fig. 6 is a perspective detail of parts relative to the tack separator; and

Fig. 7 is a perspective detail, partly in section, of the tack carrier slide and wiper mechanism.

Mounted upon the column 1 is the head frame 2 which supports the main driving shaft 3 carrying the pulley 4 which may be connected to any convenient source of power for applying necessary rotative movements to the shaft 3.

Pivotedly mounted on the head frame at 5 is the pincer "updraw" lever 6 which may be actuated from a slide 7 by means of a

cam block 8 secured to the main shaft, the construction being such that as the main shaft 3 is rotated, the updraw lever will be oscillated upon its pivotal mounting 5 in the head frame.

Connected to the updraw lever 6 is the pincer bar 9 carrying at its lower end one of the pincer jaws 10. Extending through the pincer bar 9 is the pincer closing rod 11 carrying the other pincer jaw 12, said pincer closing jaw being operatively connected to an arm 13 mounted upon the shaft 14, Fig. 1.

Loosely mounted upon the main shaft 3 is the cam block 15 from which the shaft 14 derives its movements as common in this type of machines, for causing the pincers to grip and release the stock, substantially as more fully disclosed in the patent heretofore mentioned, and as set forth in the patent to Bates, No. 1,029,840, dated June 18, 1912.

From the construction thus far described it will be apparent that upon rotation of the main driving shaft 3 the pincer jaws will be given their "updraw" movements and that they will be closed and opened provided the cam block 15 is operatively connected to the main driving shaft 3, otherwise, while the pincers may continue their "updraw" movements, they will remain open.

In order to lay the upper materials over the innersole, the pincers, in this type of machine, are given an "overdraw" movement after they have been closed upon the stock. This overdraw movement is effected by a spring-operated thrust rod 16, Fig. 1, controlled by a face formed on the rear side of the cam block 15, and connected at its forward end to the pincer bar, as usual in this type of machine, the construction being such that when the cam block 15 is rotatably connected to the main shaft 3, the pincers in addition to their gripping and updraw movements, will be given an overdraw movement to position the stock over the innersole, ready to be secured in position by suitable fastenings.

In lasting certain portions of the shoe, where the stock is excessively full, owing to the contour of the last about which it is to be placed, it is desirable to plait the upper in order that it may be more smoothly laid upon the innersole, and to this end it has been customary to give the pincers, in addition to their gripping, updraw and overdraw movements, a plaiting movement. This is effected in the present machine, from the cam block 15 which is provided with the usual track in its front side from which is actuated a lever, not shown, to oscillate a sleeve shaft 17, and a rocker 18. The construction of the means for imparting the plaiting movement to the pincers is not here illustrated and described in detail, as it is

well understood in the art, and is fully shown and described in the patents hereinbefore called to attention.

From the construction thus far described, 5 it will be apparent that the pincer gripping, overdrawing, and plaiting movements are all controlled from the single cam block 15.

In lasting certain portions of shoes, as 10 for instance in passing around the heel seat, it is unnecessary to updraw and overdraw the upper materials by means of the pincers, because the material is already sufficiently brought to the last, and a wiping action alone is sufficient so to lay the upper upon the 15 innersole that the fastenings may be inserted to secure the upper about the heel seat in lasted position. It is consequently important to suspend the pincer gripping and overdraw, and plaiting movements at 20 such times, thereby relieving the operator from the necessity of causing the shoe to dodge the pincers on each cycle of the machine operation. At other portions of the shoe, however, where the fullness of the 25 upper materials is not excessive, it is desirable to give to the pincers their gripping, updraw, and overdraw movements in a straight line, and at such times it is necessary to suspend the pincer plaiting movements. At still other times, in lasting that 30 portion of the shoe where the fullness of the upper is excessive, the pincers in addition to their gripping, updraw, and overdraw movements, should be given their 35 plaiting movement, either to the right or left.

During the lasting operation, however, the operator's hands are both employed in holding and moving the shoe for the action of 40 the lasting devices upon successive portions of the shoe. His foot is likewise employed to depress the treadle that the machine may continue its operation. It is essential, however, that the operator have under his control these various changes in the pincer 45 movements to bring them at will into accord with the character of the work presented by the different portions of the shoe, and this he should be able to do without 50 changing the established operative relation of other parts of the machine, and without disengaging his hands from the shoe or altering the position of his foot with relation to the depression of the treadle.

To this end, the present invention contemplates means for enabling the operator to dispense with or introduce the pincer closing and overdrawing movements independent of 55 any change in the relation of other of the machine parts, and while still maintaining his hands engaged with the work and his foot holding the treadle in its unchanged depressed position. The knee-controlled means is especially advantageous to the above ends, 60 because it enables the operator to change

the operative condition of the pincers by merely swinging the knee to one side or the other or holding it in the central position, and this he may do without changing his position with relation to the machine or 70 altering his foot control of the treadle or his hand control of the work.

To provide these characteristics in the machine, the cam block 15 is loosely mounted upon the main shaft 3 and is adapted to be 75 operatively connected thereto by a clutch. In the present instance, the cam block 15 has pivotally mounted thereon at 19, a latch 20 provided with a lug 21 adapted to engage a recess 23 formed in a collar 24 secured to 80 the main shaft 3. A spring 25 secured to the cam block normally acts upon the latch 20 to move it in a direction to cause the lug 21 to engage the recess 23 when the latch 25 is free to respond to the demands of the 85 spring, the construction being such that when the lug 21 and recess 23 are engaged, the cam block 15 will be caused to rotate with the main shaft and when such parts are disengaged, the cam block may remain 90 idle while the main shaft continues to rotate.

A clutch controlling lever 26 is pivotally mounted at 27 on the head frame and its upper portion is provided with means for disengaging the latch from its connection 95 with the collar 24 when said lever is moved to bring said means into operative relation with the latch and to permit engagement of the latch and collar when the said means is moved out of such relation. In the present instance of the invention, the upper end of the lever 26 is provided with a block 28, Fig. 3, having a cam portion 29 adapted to engage a lug 30 projecting at the side of the latch 20, the construction being such that if 100 the upper portion of the lever 26 is moved into position toward or adjacent the latch while the latter and the connected cam block 15 are rotating with the main shaft 3, the lug 30 will engage the cam portion of the 105 block 28 and cause the latch to be lifted to thereby disengage the lug 21 from the recess 23 of the collar, and thereupon the cam block 15 will be disengaged from operative connection with the main shaft and be 110 brought to rest. Opposite the cam portion 29 of the block 28 is a spring catch 31, the shoulder 32 of which will engage below the lug 30 when the latter rides over the cam portion 29 of the latch, and prevent rebound.

The clutch controlling lever 26, above its pivot 27, is connected to a rod, 33, Figs. 2 and 4, the other end of which enters a longitudinal recess 34 formed in a plunger 35, 125 and bears upon a light spring interposed between the end of the rod 33 and the end wall of the recess, a pin and slot connection 36 between the rod and plunger, permitting limited longitudinal movement of the rod 130

independent of the plunger. The plunger 35 is itself normally under the influence of a spring 37 tending to move the plunger to the right, Fig. 4, and turn the clutch-controlling lever 26 to disengage the upper end of the lever from the latch and thereby permit the latch and collar to operatively connect the cam block 15 and main shaft 3.

The plunger 35 has a head portion 38, Fig. 4, adapted to be engaged by a cam face 39 on the end of a rocker pivotally mounted at 40 and connected by a rod 41 with the treadle-operated starting rod 42, the construction being such that upon depression of the treadle, as usual in this type of machine, the starting rod 42 and rod 41 will be moved upwardly, thereby turning the rocker to cause its cam face to move the rod 33 against the tension of the plunger spring or to the left, Figs. 2 and 4, and place the upper end of the clutch-controlling lever 26 in position to disengage the latch 20 from the collar 24, should the lever remain in such position when the machine makes its first revolution after starting. Thus it will be seen that when the machine is at rest, the latch 20 is left in position to operatively connect the cam block 15 and the shaft 3 so that on the first revolution of the machine, the pincer will be given its gripping, updraw and overdraw movements, but at the completion of the first revolution, the latch will be disengaged from operative connection with the collar 24 and thereafter the pincer-gripping and overdraw movements will be suspended unless modified, as will be hereinafter more fully described.

This characteristic action of the machine is desirable because without it the operator would have to wait over the first turn of the machine before he could get a pull by the pincers, and inasmuch as the lasting operation is customarily commenced at a part of the shoe where the upper materials are to be updrawn and overdrawn, this would entail a loss of time and ineffective operation of the machine.

The lower end portion of the clutch-controlling lever 26 is provided with a pin or lug 43 which, in connection with means to be presently described, and under the control of the operator, may further determine whether after the first revolution of the machine, the pincers shall continue their gripping and overdraw movements, or shall suspend the same.

In the present instance of the invention, the pin or projection 43 is provided with an angular portion 44 preferably formed as a V.

Mounted upon the column 1 for rocking movement with relation thereto, is the knee lever 45, Fig. 1, carried by suitable bearings 46 for rocking movement with respect thereto. One end of said knee lever 45 is pro-

vided with a knee yoke 47 which may be appropriately connected to the knee lever adjustably, as indicated at 48. At the other side of the pivotal connection of the knee lever 45 with the column 1, said lever is provided with a diagonal way or inclined cam 49 adapted to engage a pin or roll 50 secured to a rod 51 which may be guided in a lug 52 for vertical movement with respect thereto. At its upper portion the rod 51 is provided with a head 53 pivotally connected at 54 with a rocker 55 mounted to rock upon a fixed pivotal support 56 carried by the head frame. The rocker 55 at its other end portion has secured to or formed therewith, a finger 57. In the present instance of the invention, said finger is preferably secured to the rocker by a clamping bolt 58. The finger 57 is provided with a recess 59 corresponding in general shape to the shape of the angular portion of the pin 43 and in the present instance of the invention is substantially V shaped. From the construction thus far described, it will be seen that upon rocking movement being imparted to the knee lever 45, the rod 51 will be raised or lowered, according to the direction of the rocking movement and perforce, the rocker 55 will be rocked upon its pivotal mounting 56 to either raise or lower the finger 57 relatively to the end 44 of the pin 43. When the V end portion of the pin 44 and corresponding V notch of the finger 57 are in opposed relation as indicated in Figs. 1 and 5, the clutch-controlling lever 26 will be moved by the rod 33 when the machine is operating to carry its upper end portion toward the latch 20 and effect disengagement of said latch from the collar 24, to thereby suspend the operation of the cam block 15, and perforce, the pincer-gripping and overdraw movements which are derived therefrom. Should the knee lever be turned, however, either to the right or left, the finger 57 will be raised or lowered with respect to the end of the pin 43 to bring a portion of said finger at one or the other sides of the V notch opposite the V lug of the finger 43, and the finger will in this disposition of parts, move the clutch-controlling lever 26 out of engagement with the latch 20 to thereby permit the latch to operatively engage the cam block 15 with the main shaft 3, and perforce, cause the pincer-gripping and overdraw movements.

From the construction thus far described, it will be seen that when the machine is at rest, the latch 20 is in position to operatively engage the cam block 15 with the main shaft 3, and when the operator depresses the usual treadle to start the machine, the latch-controlling lever 26 will be moved into position to engage the latch and free the cam block when the machine has made one revolution and the pincers have been given

one gripping and overdraw movement. Should the operator determine at this time to continue the pincer-gripping and overdraw movements, he will after depressing 5 the treadle to start the machine, move the knee lever to the right or left to thereby cause the finger 57 to move and retain the clutch-controlling lever 26 out of engaging position with the latch 20 as the cam block 10 continues its rotation. If, however, the operator determines that, after the first revolution of the machine and the pincer-gripping and overdraw movement incident thereto, such pincer-gripping and overdraw 15 movements shall be suspended, he will not move the knee lever, but permit it to remain in central position with the V notch of the finger 57 and the V end portion of the pin 43 in opposed relation, which permits 20 the upper end of the clutch-controlling lever 26 to be held by the plunger spring 34 in clutch-disengaging position.

The described control of the pincer-gripping and overdraw movements by the knee lever or other equivalent means actuated by 25 the body of the operator other than his hand or foot, is not tied up to any other elements of the machine construction so that such other elements may remain in previously 30 disposed relation while the operator changes at will the operative or inoperative condition of the pincer-gripping and overdraw movements.

As hereinbefore noted, it is desirable at 35 times to plait the upper during the pincer-gripping and overdraw movements, and at other times to suspend such plaiting movement of the pincers while still continuing their gripping and overdraw movements to 40 thereby effect a straight pull upon the upper materials; and to this end, the present invention contemplates that the same means for controlling the pincer-gripping and overdraw movements as by the knee lever, 45 shall be available to the operator for controlling the plaiting movements of pincers, as will now be described.

Mounted on the rocking sleeve 17 of the usual pincer-plaiting mechanism, is the collar 60 which, by its movement to the right or left, determines the direction and amount of plaiting movement given to the pincers and by its central position, suspends such plaiting movements. The details of the pincer-plaiting mechanism are not herein 55 shown, because such pincer-plaiting mechanism forms no essential part of the present invention, and is well understood by those skilled in the art.

60 The yoke 61 for moving the sleeve 60 to the right or left or to central position, is pivotally mounted upon the head frame, and in the present instance of the invention, upon the same axis 56 as the rocker 55, Figs. 1 and 5. Said yoke 61 is connected to the

sleeve 60 by the pins 62 which travel in the pathway 63 formed centrally of the collar 60. The yoke 61 extends beyond its pivotal mounting to form an arm 64 which carries a pin or roller 65. The pin or roller 65 engages a cam slot formed in the head 53. This cam slot is formed with inclined end portions 66 and 66^x as indicated in Fig. 5, which, when the knee lever is turned in one or the other directions, will act through the 70 pin or roller 65 of the yoke to move the yoke longitudinally of the rocking sleeve 17 in one direction or the other, according to whether the knee lever is swung to the right or left to thereby determine the direction 75 and amount of the plaiting movement of the pincers.

As before noted, it is desired at times to give the pincers their gripping and overdraw movements while suspending the operation of the pincer-plaiting mechanism in order to give to the pincers a straight pull; and at other times it is desirable to give to the pincers not only their gripping and overdraw movements, but also their plaiting 85 movements. To this end, the cam slot in the head 53 has a short, straight portion 67 which permits the knee lever to be swung to the right or left a short distance without turning the yoke upon its pivot, such distance being sufficient, however, to carry the finger 57 into such relation with the end 44 of the lever 26 that such lever cannot be moved into unclutching relation with the latch 20.

In order that the operator may have some determined guide to indicate to him when the parts are in the position just described, and the pincer-gripping and overdrawing motions are being imparted to the pincers while the plaiting movement is suspended, the finger 57 is provided with shallow depressions 68, adapted to engage the apex of the V end 44 of the pin 43, the construction being such that when the knee lever has 100 been swung to the right or left a sufficient distance to insure the gripping and overdrawing movements of the pincers, but not sufficiently far to introduce the plaiting movements, this fact will be made evident 105 by the shallow recesses 68 engaging the V end of the pin 43. Should the operator desire at any time to introduce the plaiting movements of the pincers while continuing their gripping and overdrawing movements, he has only to move the knee lever a greater distance in order to cause the inclined portions 66 or 66^x of the cam slot to move the yoke either to the right or left, according 110 to the direction of plait desired, and such movement merely gives additional movement to the finger 57 without changing the pincer-gripping and overdrawing operation.

When the pincer-gripping and overdraw- 130

6
ing movements are suspended, the upper materials are laid over the edge of the inner-sole sufficiently by a wiper. This wiper may be of any character suited to its purpose, but as illustrated in the present instance of the invention, the wiper is mounted for movement in an inclined path relatively to the edge of the shoe to conform to the direction of the plaits in the upper materials, as fully described in the United States Letters Patent to Bates, No. 1,029,840, dated June 18, 1912. While this character of wiper and its action may be advantageously employed in some cases, the invention herein is not dependent upon this particular form of wiper, but such wiper may be omitted and dependence placed upon the usual tack carrier or tack block for wiping the upper materials into lasted position, as 20 will be readily understood.

A lever 70, Fig. 1, is fulcrumed at 71 to a suitable bracket mounted upon the head frame, and at its upper end engages the cam slot 72 of a cam 73 secured to the main shaft. The lower end of the lever 70 is connected to the slide 74 which constitutes the tack carrier slide, the construction being such that upon rotation of the main shaft 3, the lever 70, and perforce, the tack carrier slide, will be given suitable reciprocating movements.

The tack carrier slide 74 carries the tack carrier 75 having an opening 76 therethrough, for receiving a tack from the tack feeding means, and presenting the tack to the driver. In operation, the slide bar is reciprocated to carry the tack carrier back and forth, and when the tack carrier reaches a suitable position in its rearward movement, a tack is transferred from a raceway into the aperture 76 of the tack carrier and then the tack carrier is moved forward into proper timed relation to the operation of the pincers, and may act to wipe the over-laid upper upon the innersole. A driver then forces the tack carried in the aperture of the tack carrier through the upper materials to secure them in lasted position.

Pivottally mounted at 77, Fig. 7, of the tack carrier 75, is the wiper 78 which will partake of the reciprocating movement of the tack carrier 75; and in order that the wiper 78 may be given the inclined direction already described, the rear end portion 55 of the wiper is provided with a roll 79 which engages a U guide 80, the position of which is under the control of an arm 81, Fig. 7, connected to the swing member 82, Figs. 2 and 5. The swing member 82 is 60 pivoted at 83 and at 84 it is connected to the means for controlling the plaiting mechanism whereby the direction of the U guide 80 may be appropriately changed in accordance with the direction of pincer-plaiting movements, substantially as more fully

explained in the patent to Bates, to which reference has been made.

The tacks or fastenings which are to secure the upper in lasted position, are supplied through a suitable raceway 85, and delivered to a tack separator 86, Fig. 6, which has a reciprocating movement across the end of the raceway to detach therefrom singly and deliver to the tack carrier, a tack to be placed in position for the driver. 75

Reciprocating movements are imparted to the tack separator 86 by the rack and segment 87, 88, respectively, the latter being formed as part of a yielding member 89, as usual, and normally under the influence of 80 a spring 90 against the tension of which the yielding member 89 may be appropriately moved by means of a cam 189 on the tack carrier slide and a roll 190 on the yielding member 89, to effect reciprocation of the tack 85 separator 86. In the present form of the invention, the yielding member 89 is composed of two parts, the segment carrying portion and the operating portion 91, said two portions of the member 89 being substantially of 90 the construction heretofore common in this class of devices, and the construction being such that while the tack separator 86 may be reciprocated to detach a tack from the raceway and deliver it to the tack carrier when 95 such separator movement is not obstructed, yet when there is obstruction to the tack separator movement, the two portions of the member 89 may yield to permit the tack separator to remain at rest. The general 100 construction and operation of the parts relating to the tack separator and tack supply may be as heretofore common in the art.

Changes may of course be made in the various constructions and details of the invention as hereinbefore explained, without departing from the true scope thereof as pointed out by the claims; but the described construction has been found a convenient and good, practical form of the invention. 110

Certain novel features relating to the control of the tack feeding and driving mechanism herein shown but not claimed are set forth and claimed in my copending application, Serial No. 133,491, filed November 25, 115 1916, which is a division of this application.

What is claimed is:

1. In a machine of the class described, the combination of pincers and actuating means therefor for working successive portions of 120 an upper over a last, fastening-inserting means for securing the upper in position, and knee-controlled means for permitting the attendant to suspend or continue at will the operation of the pincers while maintaining unchanged the operation of the fastening-inserting means.

2. In a machine of the class described, the combination of tack feeding and driving means, pincers and actuating means therefor 130

for working successive portions of an upper over a last, and knee controlled means for causing the pincer to remain open independently of and while the tack feeding and driving means continue in operation in previously established operative relation.

3. A machine of the class described having, in combination, means for working successive portions of an upper over a last including pincers, tack feeding and driving means, actuating devices for giving the pincers gripping and overdraw movements, and controlling means for said actuating devices movable by the knee of the attendant during the operation of the machine for rendering ineffective the gripping and overdraw movements of the pincers without disturbing the operation of the tack feeding and driving means.

20 4. A machine of the class described, having, in combination, pincers, actuating means therefor for working successive portions of an upper over a last, a wiper for wiping the upper over the last, means for controlling the operation of the machine, and knee actuated means for enabling the attendant to suspend or continue the operation of the pincer actuating means while the machine remains in operation.

30 5. In a machine of the character described, the combination of means for working successive portions of an upper over a last including pincers, actuating means for causing said pincers to grip, updraw, and overdraw the upper, and knee controlled means for permitting the attendant to suspend or introduce at will the pincer gripping and overdrawing movements during the operation of the machine.

40 6. In a machine of the character described, the combination of means for working successive portions of an upper over a last including pincers, means for imparting to said pincers their gripping, updrawing, overdrawing, and plaiting movements, and a unitary means under manual control for permitting the attendant to suspend or introduce at will the gripping, overdrawing, and plaiting movement of the pincers during the operation of the machine.

50 7. A machine of the character described, having, in combination, pincers, means for imparting to said pincers their gripping, overdrawing and plaiting movements, and manually operated means movable to a predetermined position for controlling the pincer gripping and overdrawing movements and to another position for controlling the pincer plaiting movements during the undisturbed operation of the machine.

60 8. In a machine of the character described, the combination of means including pincers, for working an upper over a last, means for causing the pincers to grip, overdraw and plait the upper, and manually operated

means movable to a predetermined position for suspending the pincer gripping, overdrawing, and plaiting movements, and to a different position for introducing the pincer gripping, overdrawing and plaiting movements.

9. In a machine of the character described, the combination of means including pincers for working an upper over a last, means for operating the pincers to cause them to grip, overdraw and plait the upper, and manually controlled means movable to a predetermined position for suspending the pincer gripping, overdrawing and plaiting movements, to another position for introducing the pincer gripping and overdrawing, while suspending the pincer plaiting movement, and to another position for introducing the pincer plaiting movement.

10. In a machine of the character described, the combination of means including pincers for working an upper over a last, means for imparting to the pincers gripping, overdrawing, and plaiting movements, and knee operated means movable to a predetermined position for suspending all of said pincer movements, to another position for introducing some of said movements, and to a third position for introducing all of said pincer movements.

11. In a machine of the character described, the combination of means including pincers for working an upper over a last, means operative upon starting the machine for imparting to said pincers gripping and overdrawing movements, and knee actuated means under control of the operator for continuing or suspending at will the pincer gripping and overdraw movements while continuing the machine in undisturbed operation.

12. In a machine of the character described, the combination of means including pincers for working an upper over a last, means operative upon starting the machine for imparting to said pincers gripping and overdrawing movements, and knee controlled means movable to different position by the attendant to continue or suspend at will the pincer gripping and overdrawing movements.

13. A machine of the character described, having in combination, means including pincers for working an upper over a last, means operative upon starting the machine for giving the pincers gripping and overdraw movements, and manually controlled means for continuing or discontinuing at will the pincer gripping and overdrawing movements and for introducing pincer plaiting movement while maintaining the speed of the machine undisturbed.

14. A lasting machine, comprising, in combination, means including pincers for working successive portions of an upper over

a last, means for causing the pincers to grip, overdraw, and plait the upper and knee controlled means movable to a predetermined position for suspending the pincer gripping, 5 overdrawing, and plaiting movements, to a point at either side of said position for introducing the pincer gripping and overdrawing movements while suspending the pincer plaiting movement, and to a further 10 point at either side of said position for introducing the plaiting movement.

15. A lasting machine of the character described, comprising in combination, means including pincers for working an upper over a last, cam means for operating the pincers, a shaft, a clutch for operatively connecting the cam means and shaft to impart to the pincers gripping and overdrawing movements, and knee controlled means for operating 20 the clutch to enable the attendant to suspend or introduce the pincer gripping and overdrawing movements during the operation of the machine.

16. In a lasting machine of the character described, the combination of means including pincers for working an upper over a last, cam means for giving the pincers gripping, overdrawing and plaiting movements, an operating shaft, a clutch for operatively 25 connecting and disconnecting the cam means and shaft, and knee controlled means for operating the clutch to suspend or introduce at will the pincer gripping, overdrawing and plaiting movements.

30 17. In a lasting machine, the combination of means including pincers for working an upper over a last, means for giving the pincers gripping and overdrawing movements, pincer plaiting mechanism actuated by said means, knee controlled devices for 35 determining the operative or inoperative condition of said means, and connections between the said devices and plaiting mechanism for suspending or introducing the pincer plaiting movement.

40 18. In a lasting machine, the combination of means including pincers for working an upper over a last by successive operations, pincer operating means for giving the pincers gripping and overdrawing movements, pincer plaiting mechanism connected to said operating means for actuation therefrom, and manually operated devices movable to a position for causing actuation 45 of said pincer operating means to effect pincer gripping and overdrawing movements and to another position for causing pincer plaiting movement.

50 19. In a lasting machine, the combination of means including pincers for working an upper over a last by successive operations, pincer operating means for giving the pincers gripping and overdrawing movements, pincer plaiting mechanism connected to said 55 means to be operated thereby, knee actuated

means for controlling at will the pincer operating means, and a cam device movable by the knee actuated means for controlling the operation of the plaiting mechanism.

5 20. In a lasting machine, the combination of pincers for gripping the upper materials of a shoe, means effective on starting the machine for insuring that the pincers have imparted to them their updraw and overdraw movements during the first cycle of 10 operation, and means for thereafter permitting the operator to continue or suspend the effective action of the pincers.

15 21. In a machine of the character described, the combination of pincers for working an upper over a last, cam means for operating the pincers, a shaft, a clutch for operatively connecting and disconnecting the cam means and shaft, knee controlled means for operating the clutch to suspend or introduce the pincer updraw and overdraw movements, and means for indicating to the operator when the knee controlled means has been moved sufficiently to introduce the pincer updraw and overdraw movements.

20 22. In a machine of the character described, the combination of pincers, means for causing the pincers to updraw, overdraw, and plait the upper materials, body or knee controlled means for determining the movements to be given the pincers, including a rocking member for introducing or suspending the updraw and overdraw movements, and a cam member for introducing or suspending the plaiting movements.

25 23. In a machine of the character described, the combination of pincers, means for giving the pincers updraw and overdraw movements, a clutch for rendering said means operative or inoperative, and means for controlling the clutch comprising a manually operated rocker having a finger provided with a notch, and a lever having a pin or projection adapted to be engaged by or disengaged from the notch in the finger.

30 24. A machine of the class described having, in combination, pincers, a wiping device, a shaft, means actuated from said shaft for operating the wiping device and imparting updrawing and plaiting movements to the pincers, and means movable by the knee of the attendant to different positions to cause the pincer updraw to be effective or ineffective and plaiting movements to occur or to cease at will while the wiping device continues in operation.

35 25. A machine of the class described comprising, in combination, pincers, operating mechanism for closing the pincers, swinging them laterally to plait the upper, and moving them transversely of the edge of the innersole to overlay the upper on the inner-

sole, and knee controlled means for making said operating mechanism inoperative to close the pincers and inoperative to swing the pincers laterally for plaiting the upper.

5 26. A machine of the class described, comprising, in combination, pincers, a wiping device, operating mechanism for the pincers and wiping device, treadle controlled means for effecting the operation of said mechanism, and knee controlled means for enabling the attendant to render the pincers inoperative while the wiping device continues to run.

15 27. A machine of the class described having, in combination, pincers adapted to work on different parts of the shoe successively, means for effecting pincer updrawing, plaiting, and overdrawing movements, and knee controlled means for enabling the attendant 20 to suspend the updrawing, overdrawing and plaiting functions of the pincers by movement of said means to one position, and to suspend the plaiting function of the pincers while continuing the updrawing and over- 25 drawing functions of the pincers by movement of said knee controlled means to another position.

30 28. A machine of the class described having, in combination, a wiping device continuously operative while the machine is running, pincers having closing, overdrawing and updrawing movements, means for imparting plaiting movements to the pincers, manually controlled means for rendering the plaiting mechanism inoperative at 35 will, and means operated by said manually controlled means for causing the pincers to be effective or ineffective to do their work.

29. A machine of the class described having, in combination, a wiping device continuously operative while the machine is 40 running, pincers having closing, overdrawing and updrawing movements, means for imparting plaiting movements to the pincers, manually controlled means for rendering the plaiting mechanism inoperative at 45 will, and means operated by said manually controlled means for discontinuing at will the closing movement of the pincers.

30. A machine of the class described having, in combination, a wiping device continuously operative while the machine is running, pincers having closing, overdrawing and updrawing movements, means for imparting plaiting movements to the pincers, manually controlled means for rendering the plaiting mechanism inoperative at 50 will, and means operated by said manually controlled means for discontinuing at will 55 the overdrawing movement of the pincers.

31. A machine of the class described having, in combination, a wiping device continuously operative while the machine is running, pincers having overdraw and up- 60 draw movements, means for imparting plait- 65 ing movements to the pincers, treadle controlled means for effecting discontinuance of the pincer operation after the first cycle, and manually controlled means for introducing plaiting movements of the pincers 70 and for rendering the treadle controlled means ineffective to discontinue operation of the pincers.

In testimony whereof I have signed my name to this specification.

THOMAS H. SEELY.
